UNITED STATES PATENT OFFICE

JOHN T. BEECHLYN, OF WORCESTER, MASSACHUSETTS

PEELING KNIFE

Application filed October 27, 1927. Serial No. 229,248.

This invention relates to knives for paring fruits and vegetables, and, while it has general usefulness in this class, it is particularly adapted to potato paring.

5 The objects of the invention are to provide a knife, which, by a special contour of its blade will permit speedy and economic paring of the materials in question, and which at the same time will be facile in operation 10 by virtue of proper disposition of the cutting sections of the blade with relation to the axis of the handle; to provide a knife which may easily be kept in a sanitary condition and suspended when not in use, and to provide 15 a construction which can be inexpensively manufactured with a very slight waste.

Other objects and advantages of the invention will appear hereinafter.

Reference is to be had to the accompanying 20 drawings in which

Fig. 1 is a perspective view showing a preferred form of the knife; and

Fig. 2 is a sectional view thereof, showing its application in paring an apple.

25 The handle is formed from a metallic strip 10, slightly channeled, or concaved along the inside, and bent in the form of an elongated loop. At one extremity the ends are bent to overlap, and at this point 11 the arc of the 30 channel is preferably reversed to make it concave outside. Between the overlapping ends is secured, as by rivet 12, the upturned shank 14 of the knife blade 13. The joining of the several layers of metal at this point 35 may be effected by a spot welding operation, or, as shown in the drawing, the fastening may be secured by means of the rivet 12, with the curved form of the joined sections providing an effective lock against any torsional displacement.

40 From the point of junction with the lower side of the handle, which occurs at the extreme edge of the handle, the free portion of the blade is curved upward and forward in the general direction of the longitudinal axis 45 of the handle. This portion forms the chief cutting section of the blade which, by its contour, is well adapted to the paring of generally convex areas, with a minimum loss of 50 useful material. The central part of the

blade is approximately in the form of an arc of a cylinder with its axis transverse to the axis of the handle.

In Fig. 2 is shown the extreme thinness of peels cut by the improved blade. I am aware that curved blades have before this been applied to certain forms of knives, particularly in connection with citrus fruit. In such knives, however, it has been customary to join the blade to the handle at a point 55 lying substantially in the axis of the latter. As a consequence the effective center of such curved blades has been situated distinctly outside the axis of the handle, resulting in a torsional moment exerted on the latter, when 60 the knife is put to use.

65 It is a particular object of the present construction to obtain a condition where the chief cutting sections of the blade will lie substantially in or near the axis of the handle. 70 In this way the efficiency of operation is promoted.

75 A further advantage resulting from terminating the cutting edge at the lower extremity of the handle on the side of little curvature of the blade, lies in the fact that in paring a curved object the handle, and thereby the hand of the operator, may be brought closer to the work, and in this way a more favorable leverage obtained.

80 To facilitate the paring of small areas having little curvature, as found in many vegetables, especially potatoes, the curvature of the blade is reversed near its free end at 15. 85 The disposition of this scooplike section is such as to bring its effective center substantially in the axis of the knife.

88 Although I have illustrated and described only two forms of the invention I am aware of the fact that other modifications can be made therein by any person skilled in the art without departing from the scope of the invention as expressed in the claims. Therefore, I do not wish to be limited in these respects but what I do claim is:—

90 1: As an article of manufacture, a peeling knife comprising a blade and a handle, the handle being formed by a metallic strip bent into an elongated loop with ends overlapping at one extremity, and the butt end of the blade 100

bent substantially at right angles to the cutting portion and fastened between the aforesaid overlapping ends of the handle.

2. As an article of manufacture, a peeling knife comprising a blade and a handle, the handle being formed by a metallic strip bent into a loop with the free ends overlapping and concaved and the butt end of the blade bent substantially at right angles to the cutting portion, concaved like said ends, and entering between said overlapping ends and fastened therein.

3. As an article of manufacture, a peeling knife comprising a handle formed of a metallic strip, said strip being in the general form of a rectangle, the two ends of the strip overlapping toward each other from opposite sides and a blade, the tang of the blade extending into the space between the overlapping ends and secured therewith and the blade extending therefrom in a general longitudinal direction.

4. As an article of manufacture, a peeling knife comprising a blade and a handle, the blade having its inner end entering one end of the handle transversely to the axis of the handle at a point at one side of the handle and secured thereon, the middle portion of the blade being concave on the side toward said point and lying in a plane near said axis, and having a reverse curvature near its free end, for the purpose described.

In testimony whereof I have hereunto affixed my signature.

JOHN T. BEECHLYN.
